TOY TRUCK

Richard H. Benton, Box 51, The Sea Ranch,
Calif. 95445

Filed June 2, 1969, Ser. No. 17,440

Term of patent 14 years

Int. Cl. D21—02

U.S. Cl. D34—15

Fig. 1

Fig. 2

Fig. 3

FIG. 1 is a perspective view, taken from the right side and slightly above and to the front, of a toy truck showing my new design.

FIG. 2 is a side view, taken from the left side, of the truck of FIG. 1; and

FIG. 3 is a front view of the truck of FIG. 1, the bottom and top views being conventionally plain.

I claim:

The ornamental design for toy truck, substantially as shown and described.
